UNITED STATES PATENT OFFICE.

CHARLES S. BARON, OF TIFFIN, OHIO.

TOP FOR JUGS, &c.

1,115,768.

Specification of Letters Patent.

Patented Nov. 3, 1914.

Application filed March 1, 1912 Serial No. 680,956.

To all whom it may concern:

Be it known that I, CHARLES S. BARON, of Tiffin, in the county of Seneca, and in the State of Ohio, have invented a certain 5 new and useful Improvement in Tops for Jugs, &c., and do hereby declare that the following is a full, clear, and exact description thereof.

The object of my invention is to provide 10 a top or cover for syrup and other jugs, jars, steins, etc., having a connection with the vessel that has the important characteristic of secure, but easy and, therefore, inexpensive application and detachability 15 from the vessel, and in particular my object is to provide a connecting means requiring a minimum of metal and yet affording a stout, firm support.

In the accompanying drawings—Figure 20 1 is a perspective view of enough of a syrup jug to illustrate an embodiment of my invention; Fig. 2 is a vertical section thereof; Fig. 3 is a perspective view showing the parts separated, and illustrating 25 a different embodiment of my invention; and Fig. 4 is a view similar to Fig. 2, illustrating still another embodiment of my invention.

The syrup jug 10 illustrated, and its 30 hinged cover 11, are in general of ordinary construction. The design of the jug and the form or shape of the cover may be varied from what is illustrated without departure from the scope of my invention.

35 The cover is a hinged or pivoted one having at the handle side of the jug an upturned handle piece 12 and a pair of rearwardly projecting hinge ears 13 through which, and through similar ears 14 on an attaching 40 clip 15, a pivot pin 16 passes around which is placed a coil spring 17 which, at one end bears on the top of the clip and at the other end bears against the thumb piece and yieldingly holds the lid or cover shut, as is usual.

45 The attaching clip 15 is in the form of an inverted U, it comprising a top cross piece and two downwardly extending legs which, respectively, are seated in vertical channels or recesses 180 on opposite sides of an out-

wardly projecting block or lug 18 upon the 50 jug, and near the top thereof and either or both of said legs at its lower end has a latch form to interlock with a suitable projection on said lug to detachably connect the clip thereto. As shown in Figs. 1 and 2, 55 the latch 19 is formed by a shoulder produced by a bend in the lower part of the leg which leaves the end of the lug sufficiently free so that it may be readily caught by the thumb to disengage the leg from the 60 lug when it is desired to move the clip and the attached cover from the vessel, and but one of the legs is thus formed, the other being a simple straight piece. As shown in Fig. 3 the latch is in the form of a rounded 65 teat 20 formed by pressing a part of the metal leg inward, and a correspondingly shaped cavity 200 is formed in the side of the jug lug, and in this case both legs are provided with the latch. As shown in Fig. 70 4, the latch is in the form of a hole or slot 21 punched in one of the legs which co-operates with a similarly shaped lug 22 formed on a side of the jug lug 18.

It will be evident that but a minimum 75 of metal is required to make my clip, and yet by reason of its form and that of the lug on the jug, a stiff support is provided so that accidental disengagement of the cover from the jug cannot occur, and yet most 80 easily and conveniently the cover can be applied to and removed from the jug or vessel.

As shown in Figs. 1 and 2, the hinge lugs on the cover are formed on a piece separate from the handle 23, the latter having on 85 opposite sides lugs that are turned over the hinge ears carrying member, but, of course, the hinge ears of the cover and the hand piece may be integral, as shown in Fig. 4.

It will be understood that the latch-forming leg has sufficient elasticity to enable it to be readily sprung into and out of engagement with its interlocking projection or member on the lug.

Having thus described my invention what 95 I claim is—

The combination of a vessel, its cover, a detachable clip connecting the cover and

vessel, said clip comprising a top cross piece with an upturned flange having extremities that form hinge-ears for the cover, and downwardly extending legs whose lower ends are free, and a lug on the vessel having a leg-receiving channel, the lug and leg having coöperating latch-forming members, and the leg being laterally movable on its

connection with the top of the clip to latch and unlatch it.

In testimony that I claim the foregoing I have hereunto set my hand.

CHARLES S. BARON.
